UNITED STATES PATENT OFFICE.

EMMA L. LARRABEE, OF WEST PALM BEACH, FLORIDA.

INFANT-BINDER.

1,388,867.

Specification of Letters Patent. Patented Aug. 30, 1921.

Application filed September 1, 1920. Serial No. 407,355.

To all whom it may concern:

Be it known that I, EMMA L. LARRABEE, a citizen of the United States, residing at West Palm Beach, in the county of Palm Beach and State of Florida, have invented certain new and useful Improvements in Infant-Binders, of which the following is a specification.

This invention relates to certain new and useful improvements in infant binders and it has for its objects among others to provide a simple, improved, and efficient one-piece binder, adjustable for shorter or taller, or for larger or smaller infants.

It has for a further object to provide a device of this character having narrow bands which pass around the body of the infant, one over the other and one through a slot, thus forming a binder directly where it is needed, right over the navel, leaving the thorax unsuppressed, thus avoiding pain or injury to the child from its heart, lungs, stomach and liver being so bound up as to cause pain and crying, usually considered colic. It also supports the back, and as it spreads over the shoulders it is kept from rolling and being uncomfortable over the stomach, the band passing through the slot raises it just enough to make the proper curve so that it will fit under the stomach and will not move up. It is much easier for inexperienced mothers to use as it is secured over the shoulder so that it cannot slip around or drop down and will at all times stay right where it is affixed.

Other objects and advantages of the invention will hereinafter appear and the novel features thereof will be particularly pointed out in the appended claims.

The invention, in its preferred form, is clearly illustrated in the accompanying drawings, which, with the numerals of reference marked thereon, form a part of this specification, and in which—

Figure 1 is a perspective view showing the application of the binder.

Fig. 2 is a rear view.

Fig. 3 is a view of the piece of material constituting the binder.

Fig. 4 is a cross section on the line 4—4 of Fig. 2.

Like numerals of reference indicate like parts throughout the different views.

Referring to the drawing,

1 designates the garment or binder as a whole before it is applied. It is made of

a suitable fabric, such as cotton cloth or linen cut to the shape shown in Fig. 3, having its edges provided with a hem or binding 2, as found most expedient, the body portion 3 being formed with oppositely extended bands or strap portions 4 and 5, as shown in Fig. 3, one at each end, and at a point nearer to one end of the body portion than the other with a vertical slot 6 which may be provided with a hem or binding 7, as indicated in Fig. 3.

The top edge of the body portion 3 is provided with two pairs of extensions 8 and 9 and 10 and 11, which are likewise provided with a binding or hem, as shown at 12. This constitutes the binder. When it is applied as shown in Figs. 1 and 2, it constitutes what may be termed a shirt portion and a bandage, it being understood, however, that such shirt portion and bandage are all integral, being in one and the same piece, and in its application there are no buttons or button-holes employed.

The mode of application will be evident from the drawing. The binder is placed around the body of the infant, the extensions 8, 9, and 10, 11, extended over the shoulders and overlapped and united by means of safety-pins or the like 13. The body portion 3 is overlapped at the back, as seen in Fig. 2, and the overlapped portions at the neck united by a safety-pin or the like 14, as seen in Fig. 2. The flap portion 4 is passed through the slot 6 and the flap portion 5 is lapped thereover, as seen in Fig. 1, and the overlapped portions secured by safety-pins 15 and 16, as seen in Fig. 1.

It will thus be seen that the device is readily adjustable; there are no buttons to annoy the infant and the binder can be quickly and easily applied, and as readily removed. The recesses 17 and 18 between the extensions 8 and 9 and 10 and 11 form the arm-holes and the space 19 between the extensions 9 and 10 forms the front of the neck portion when the binder is applied.

Modifications in detail may be resorted to without departing from the spirit of the invention or sacrificing any of its advantages.

What is claimed as new is:—

1. An infant binder formed of a single piece of unstiffened material comprising a body portion with a transverse slit and a flap at each end forming extensions of the body

portion at the bottom, one of said flaps adapted to pass through the slit when the binder is applied, the upper edge of the body portion being formed with extensions in 5 pairs adapted to overlap over the shoulder of the infant, said flaps being adapted to pass around the body of an infant one over the other.

2. An infant binder formed of a single 10 integral piece of material with one side edge substantially straight throughout its length,

extensions at such edge at the ends forming bands, the opposite edge being formed with two pairs of extensions adapted to overlap over the shoulders of the infant, said edge 15 being formed between said extensions with a space forming the front of the neck portion, there being a transverse slot in the body portion to receive one of said bands.

In testimony whereof I affix my signature. 20

EMMA L. LARRABEE.
